(57) **ABSTRACT**

A flush toilet includes: a toilet main unit having a bowl portion, and a water conduit formed in the toilet main unit and configured to supply flush water into the bowl portion. The water conduit has: a first water-guiding portion extending from a water supply portion to a first spout port located on one of right and left sides of the bowl portion; and a second water-guiding portion extending from the water supply portion to a second spout port located on the other of the right and left sides of the bowl portion. The water supply portion is located at a right-sided or left-sided position in a right and left direction. The flush water is supplied to the water supply portion in a direction inclined with respect to a front and back direction and intersected with an inside surface of the water supply portion, as seen in plan view.

FIG.1

FIG.2

FIG.3

FIG.4

FIG.5

FIG.6

1
FLUSH TOILET

TECHNICAL FIELD

The present invention pertains to a flush toilet, and more particularly to a flush toilet for flushing a toilet main unit with flush water.

BACKGROUND ART

Conventionally, as set forth in JP-B-6332606, for example, a flush toilet has been known wherein the flush toilet comprises a bowl portion and a rim spout port configured to spout flush water along a rim portion and wherein the flush water spouted from the rim spout port along the rim portion performs a flush as it circulates (swirls) over the interior of the bowl portion.

More specifically, as described in JP-B-6332606, a water conduit for supplying the flush water to the rim spout port (and thus to the interior of the bowl portion) has a first water-guiding portion extending from a water supply portion (branch portion), where the flush water is supplied to the water conduit, toward one of right and left sides of the bowl portion, and a second water-guiding portion extending from the water supply portion (branch portion) toward the other of the right and left sides of the bowl portion. The water supply portion (branch portion) is located at a central position in the right and left direction with respect to the bowl portion.

Patent Document List

JP-B-6332606

SUMMARY OF INVENTION

Technical Problem

Recently, it has been studied to make a flush toilet more compact in order to improve the design quality thereof. For example, it has been studied to make a flush toilet more compact in the forth and back direction in order to achieve a flush toilet whose forward projection is smaller.

Conventionally, as described in JP-B-6332606, the water supply portion (branch portion) is located at a central position in the right and left direction with respect to the bowl portion. The inventors of the present invention have been studied to make a flush toilet more compact in the forth and back direction by shifting the water supply portion (branch portion) from the central position to a right-sided or left-sided position.

The present invention has been made under the above background. The object of the present invention is to provide a flush water whose size in a forth and back direction thereof can be made compact.

Solution to Problem

The present invention is a flush toilet including: a toilet main unit having a bowl portion; a water conduit formed in the toilet main unit and configured to supply flush water into the bowl portion; wherein the water conduit has: a first water-guiding portion extending from a water supply portion, where the flush water is supplied to the water conduit, to a first spout port located on one of right and left sides of the bowl portion; and a second water-guiding portion extending from the water supply portion to a second spout port located on the other of the right and left sides of the

2

bowl portion; the water supply portion is located at a right-sided or left-sided position in a right and left direction with respect to the bowl portion; the flush water is supplied to the water supply portion in a direction inclined with respect to a front and back direction and intersected with an inside surface of the water supply portion, as seen in plan view.

According to the above feature, since the water supply portion is located at a right-sided or left-sided position in a right and left direction with respect to the bowl portion, the size of the flush toilet can be made compact in the forth and back direction.

In addition, in the present invention, if an angle at which the flush water is supplied to the water supply portion is adjusted, a ratio (distribution ratio) between an amount of the flush water supplied to the first water-guiding portion (i.e., an amount of the flush water to be spouted from the first spout port) and an amount of the flush water supplied to the second water-guiding portion (i.e., an amount of the flush water to be spouted from the second spout port) can be adjusted to a desired value.

It is preferable that the flush water is supplied to the water supply portion in a direction substantially perpendicular to a tangential direction of the inside surface of the water supply portion. In the present specification, the term "substantially perpendicular" means the range of about 75 degrees to 105 degrees.

As a concrete structure, in an preferable embodiment, the flush water may be supplied to the water supply portion by a straight nozzle extending in a direction inclined with respect to the front and back direction and intersected with the inside surface of the water supply portion, as seen in plan view; the straight nozzle may be connected to a water supply tube; and the water supply tube may have a proximal portion extending in the front and back direction, a distal portion connected to the straight nozzle and extending in the same direction as the straight nozzle, and a bend portion bending from the proximal portion to the distal portion.

According to the above embodiment, an operation for setting the nozzle is easy. In addition, a space in which the nozzle is to be set can be also made compact.

Alternatively, in another preferable embodiment, the flush water may be supplied to the water supply portion by a bend nozzle; the bend nozzle may have a proximal portion extending in the front and back direction, a distal portion extending in a direction inclined with respect to the front and back direction and intersected with the inside surface of the water supply portion as seen in plan view, and a bend portion bending from the proximal portion to the distal portion; and the bend nozzle may be connected to a water supply tube extending in the front and back direction.

According to the above embodiment as well, an operation for setting the nozzle is easy. In addition, a space in which the nozzle is to be set can be also made compact.

Alternatively, in another preferable embodiment, the flush water may be supplied to the water supply portion by a water supply passage extending in a direction inclined with respect to the front and back direction and intersected with the inside surface of the water supply portion, as seen in plan view; and the water supply passage is connected to a water supply tube via a buffer chamber which allows the flush water to temporarily stay.

According to the above embodiment, since the flush water is allowed to temporarily stay in the buffer chamber, effects caused by a direction in which the flush water is supplied from the water supply tube into the buffer chamber can be

reduced, so that the flush water can be more precisely supplied to the water supply section along the direction of the water supply passage.

In this case, more preferably, the buffer chamber has a wall formed at a position against a direction in which the flush water is supplied from the water supply tube into the buffer chamber.

According to the above feature, the effects caused by the direction in which the flush water is supplied from the water supply tube into the buffer chamber can be more reduced, so that the flush water can be much more precisely supplied to the water supply section along the direction of the water supply passage.

In addition, it is preferable that the buffer chamber has a bottom surface inclined downward toward the water supply portion.

According to the above feature, it can be inhibited that the flush water remains in the buffer chamber.

Advantageous Effects of Invention

According to the feature of the present invention, since the water supply portion is located at a right-sided or left-sided position in a right and left direction with respect to the bowl portion, the size of the flush toilet can be made compact in the forth and back direction.

BRIEF DESCRIPTION OF DRAWINGS

FIG. 1 is a side cross-sectional view showing a flush toilet according to a first embodiment of the present invention;

FIG. 2 is a plan view showing a main toilet unit of the flush toilet according to the first embodiment of the present invention;

FIG. 3 is a cross section view taken along line III-III of FIG. 2;

FIG. 4 is a plan view showing a main toilet unit of a flush toilet according to a second embodiment of the present invention;

FIG. 5 is a plan view showing a main toilet unit of a flush toilet according to a third embodiment of the present invention; and

FIG. 6 is a plan view showing a main toilet unit of a flush toilet according to a fourth embodiment of the present invention.

DESCRIPTION OF EMBODIMENTS

With reference to the attached drawings, we explain the flush toilet according to the first embodiment of the present invention. FIG. 1 is a side cross-sectional view showing the flush toilet according to the first embodiment of the present invention, FIG. 2 is a plan view showing a main toilet unit of the flush toilet according to the first embodiment of the present invention, and FIG. 3 is a cross section view taken along line III-III of FIG. 2.

It should be noted that any embodiment of the present invention will be described based on the following assumption: a "right side" is defined when viewing a toilet main unit 2 rearwardly from a front side thereof; and a "left side" is also defined when viewing the toilet main unit 2 rearwardly from the front side thereof.

As shown in FIGS. 1 to 3, the flush toilet 1 according to the first embodiment of the present invention has a toilet main unit 2 made of porcelain or the like. A water storage tank 4 as a flush water tank is provided on a rear portion of

the toilet main unit 2. The water storage tank 4 is connected to a water supply source (not shown) such as a public water system.

When an operation lever or button (not shown) provided on the water storage tank 4 is operated, the flush water is discharged to perform a flush. More specifically, when the operation lever or button is operated, a discharge valve (not shown) of the water storage tank 4 is opened so that a predetermined amount of the flush water (for example, 6 liters) is supplied from the water storage tank 4 to a supply port (not shown) provided on the rear side of the main toilet unit 2.

The flush toilet 1 according to the first embodiment can be used as a water-saving type of flush toilet using 3 liters to 6 liters of the flush water from the water storage tank 4 to perform a flush, more preferably as a water-saving type of flush toilet using 4.8 liters to 6 liters of the flush water from the water storage tank 4 to perform a flush.

Instead of the water storage tank 4, another water supply device may be used, such as a flush valve that can supply a predetermined amount of the flush water.

A bowl portion 8 is formed on an upper side of a front portion of the main toilet unit 2. A water pooling region 12 is formed at a lower part of the bowl portion 8, and a predetermined amount of water is pooled in the water pooling region 12. An initial level of the pooled water is indicated by the sign W0. A lower end of the water pooling region 12 is connected to an inlet 14a of a discharge trap pipe 14. The discharge trap pipe 14 extends rearward from the inlet 14a. A rear end 14b of the discharge trap pipe 14 is connected to a discharge pipe (not shown) provided under a floor surface.

Inside the main toilet unit 2, there is provided a water conduit 60 which is configured to guide the flush water supplied from the supply port provided on the rear side of the main toilet unit 2 toward the bowl portion 8.

The water conduit 60 has a first water-guiding portion 61 extending from a water supply portion 70, where the flush water is supplied to the water conduit 60, to a first spout port 38 located on the left side (on one of right and left sides) of the bowl portion 8, and a second water-guiding portion 62 extending from the water supply portion 70 to a second spout port 40 located on the right side (on the other of the right and left sides) of the bowl portion 8. In addition, as a feature of the present embodiment, the water supply portion 70 is located at a left-sided portion (either at a right-sided portion or at a left-sided position) in a right and left direction with respect to the bowl portion 8.

As shown in FIG. 2, the first water-guiding portion 61 and the second water-guiding portion 62 extend along an inside surface of the water supply portion 70 (and outside an outer peripheral surface of the bowl portion 8) as seen in plan view, respectively. The flush water is supplied to the water supply portion 70 in a direction inclined with respect to a front and back direction and intersected with the inside surface of the water supply portion 70 (as well as intersected with the outer peripheral surface of the bowl portion 8) as seen in plan view. In particular, in the present embodiment, the flush water is supplied to the water supply portion 70 in a direction substantially perpendicular to a tangential direction of the inside surface of the water supply portion 70.

The first water-guiding portion 61 is formed to extend from the water supply portion 70 substantially toward the front portion of the main toilet unit 2. The second water-guiding portion 62 is formed to extend from the water supply

portion **70** substantially toward a right side of the main toilet unit **2** and subsequently bend back to the second spout port **40**.

In addition, in the present embodiment, as shown in FIG. 2, the first water-guiding portion **61** and the second water-guiding portion **62** are smoothly continuous. The tangential direction of the first water-guiding portion **61** at the water supply portion **70** and the tangential direction of the second water-guiding portion **62** at the water supply portion **70** are substantially identical. The flush water is supplied to the water supply portion **70** in a direction substantially perpendicular to both the tangential directions.

Furthermore, in the present embodiment, the flush water is supplied to the water supply portion **70** by a straight nozzle **71** extending in a direction inclined with respect to the front and back direction and intersected with the inside surface of the water supply portion **70** (as well as intersected with the outer peripheral surface of the bowl portion **8**) as seen in plan view. The straight nozzle **71** is connected to a water supply tube **72**. The water supply tube **72** has a proximal portion **72a** extending in the front and back direction, a distal portion **72c** connected to the straight nozzle **71** and extending in the same direction as the straight nozzle **71**, and a bend portion **72b** bending from the proximal portion **71a** to the distal portion **71c**.

The bowl portion **8** also has a waste receiving surface **16** formed in a bowl shape, and a rim portion **18** formed at a top edge part of the bowl portion **8** and configured to spout the flush water toward the waster receiving surface **16**.

More specifically, the rim portion **18** is formed at substantially an entire circumference of the top edge part of the bowl portion **8**, so that the rim portion **18** can guide the flush water in a well-balanced manner to respective regions in the bowl portion **8**. The rim portion **18** is located above the waste receiving surface **16**. An inner wall surface of the rim portion **18** is a rim water-passage outer wall surface **34**. An upper part of the rim water-passage outer wall surface **34** is formed to project inwardly. In addition, a rim water-passage bottom wall surface **24** of the rim portion **18** is formed to extend horizontally inwardly. Thereby, a rim water passage **20** is formed on the rim water-passage bottom wall surface **24**.

The rim water-passage bottom wall surface **24** is formed in a shelf shape in a substantially flat horizontal manner over substantially the entire circumference of the bowl portion **8**. Thereby, the flush water that flows on the rim water-passage bottom wall surface **24** of the rim water passage **20** can form a flow around substantially the entire circumference of the upper part of the bowl portion **8**.

In addition, in the present embodiment, in a transition region where the first water-guiding portion **61** and the rim water passage **20** are connected, an outer wall surface **61c** of the first water-guiding portion **61** and the rim water-passage outer wall surface **34** of the rim portion **18** are continuously formed substantially in a flat manner. Thereby, the flush water can smoothly flow from the outer wall surface **61c** of the first water-guiding portion **61** to the rim water-passage outer wall surface **34** of the rim portion **18**.

Similarly, in the present embodiment, in a transition region where the second water-guiding portion **62** and the rim water passage **20** are connected, an outer wall surface **62c** of the second water-guiding portion **62** and the rim water-passage outer wall surface **34** of the rim portion **18** are continuously formed substantially in a flat manner. Thereby, the flush water can smoothly flow from the outer wall

surface **62c** of the second water-guiding portion **62** to the rim water-passage outer wall surface **34** of the rim portion **18**.

In addition, in the present embodiment, in a vicinity of the first spout port **38**, a direction in which a central axis **A1** of the first water-guiding portion **61** extends and a flow direction **A2** of the flush water that goes along the rim water passage **20** in a left-hand region of the bowl portion **8** are substantially identical. Thereby, the flush water spouted from the first spout port **38** flows in substantially the same direction on the rim water passage **20**, and thus the flush water can flow around the rim water passage **20** with its power substantially maintained (with the flow amount and the flow speed substantially maintained).

Similarly, in the present embodiment, in a vicinity of the second spout port **40**, a direction in which a central axis **A3** of the second water-guiding portion **62** extends and a flow direction **A4** of the flush water that goes along the rim water passage **20** in a right-hand rear region of the bowl portion **8** are substantially identical. Thereby, the flush water spouted from the second spout port **40** flows in substantially the same direction on the rim water passage **20**, and thus the flush water can flow around the rim water passage **20** with its power substantially maintained (with the flow amount and the flow speed substantially maintained).

Next, an operation (action) of the flush toilet **1** according to the first embodiment is explained.

In order to perform a flush, the operation lever or button (not shown) in an operation panel (not shown) is operated so that the discharge valve (not shown) provided in the water storage tank **4** is opened. Then, a predetermined amount of the flush water (for example, 6 liters) is supplied from the water storage tank **4** into the main toilet unit **2** through the supply port (not shown) provided on the rear side of the main toilet unit **2**. More specifically, the flush water is supplied into the water supply portion **70** through the water supply tube **72** and the straight nozzle **71**.

Subsequently, the flush water supplied from the water supply portion **70** to the water conduit **60** is divided into the first water-guiding portion **61** and the second water-guiding portion **62**.

The flush water spouted from the first spout port **38** through the first water-guiding portion **61** flows on the rim water passage **20** along the flow line **A2**, and swirls down from the rim water-passage bottom wall surface **24** toward the waste receiving surface **16** while washing the bowl portion **8**.

Similarly, the flush water spouted from the second spout port **40** through the second water-guiding portion **62** flows on the rim water passage **20** along the flow line **A4**, and swirls down from the rim water-passage bottom wall surface **24** toward the waste receiving surface **16** while washing the bowl portion **8**.

The flush water that has swirled down while washing the bowl portion **8** is discharged from the discharge trap pipe **14** together with waste. Then, a sequence of flush operations for the main toilet unit **2** is completed.

According to the flush toilet **1** of the first embodiment as described above, since the water supply portion **70** is located at the left-sided position (either at a right-sided portion or at a left-sided position) in the right and left direction with respect to the bowl portion **8**, the size of the flush toilet **1** can be made compact in the forth and back direction.

In addition, according to the flush toilet **1** of the first embodiment, the first water-guiding portion **61** and the second water-guiding portion **62** are smoothly continuous, the tangential direction of the first water-guiding portion **61**

at the water supply portion 70 and the tangential direction of the second water-guiding portion 62 at the water supply portion 70 are substantially identical, and the flush water is supplied to the water supply portion 70 in a direction substantially perpendicular to both the tangential directions. Thus, the flush water can be divided into the first water-guiding portion 61 and the second water-guiding portion 62 in accordance with a desired ratio, and the power (the flow amount and the flow speed) of the respective flush waters can be also maintained sufficiently.

In addition, according to the flush toilet 1 of the first embodiment, the flush water is supplied to the water supply portion 70 by the straight nozzle 71 extending in the direction inclined with respect to the front and back direction and intersected with the inside surface of the water supply portion 70 (as well as intersected with the outer peripheral surface of the bowl portion 8) as seen in plan view, and the straight nozzle 71 is connected to the water supply tube 72. The water supply tube 72 has the proximal portion 72a extending in the front and back direction, the distal portion 72c connected to the straight nozzle 71 and extending in the same direction as the straight nozzle 71, and the bend portion 72b bending from the proximal portion 71a to the distal portion 71c. According to these features, an operation for setting the straight nozzle 71 is easy. In addition, a space in which the straight nozzle 71 is to be set can be also made compact.

In addition, in the flush toilet 1 of the first embodiment, by adjusting an angle at which the flush water is supplied to the water supply portion 70, a ratio (distribution ratio) between the amount of the flush water supplied to the first water-guiding portion 61 (i.e., the amount of the flush water to be spouted from the first spout port 38) and the amount of the flush water supplied to the second water-guiding portion 62 (i.e., the amount of the flush water to be spouted from the second spout port 40) can be adjusted to a desired value. It is relatively easy to perform this adjustment by changing a setting angle of the straight nozzle 71 with respect to the water supply portion 70.

Next, FIG. 4 is a plan view showing a main toilet unit of a flush toilet according to a second embodiment of the present invention. In the second embodiment, a bend nozzle 81 and a straight water supply tube 82 are used, instead of the straight nozzle 71 and the bend water supply tube 72.

More specifically, in the second embodiment, the flush water is supplied to the water supply portion 70 by the bend nozzle 81. The bend nozzle 81 has a proximal portion 81a extending in the front and back direction, a distal portion 81c extending in a direction inclined with respect to the front and back direction and intersected with the inside surface of the water supply portion 70 (as well as intersected with the outer peripheral surface of the bowl portion 8) as seen in plan view, and a bend portion 81b bending from the proximal portion 81a to the distal portion 81c. The bend nozzle 81 is connected to the straight water supply tube 82 extending in the front and back direction.

In order to facilitate an operation for setting the bend nozzle 81, the water conduit 60 is expanded in a vicinity of the water supply portion 70.

The other structure of the second embodiment is substantially the same as the first embodiment explained with reference to FIGS. 1-3. In FIG. 4, the same portions as those of the first embodiment are shown by the same reference numerals, and detailed explanation thereof is omitted.

According to the second embodiment, an operation for setting the bend nozzle 81 is easy. In addition, a space in which the bend nozzle 81 is to be set can be also made compact.

Next, FIG. 5 is a plan view showing a main toilet unit of a flush toilet according to a third embodiment of the present invention. In the third embodiment, a buffer chamber which allows the flush water to temporarily stay is used to guide the flow direction of the flush water toward the water supply portion 70, instead of a member in which a bend flow path has been formed (such as the bend water supply tube 72 or the bend nozzle 81).

Specifically, in the third embodiment, the flush water is supplied to the water supply portion 70 by a water supply passage 91 extending in a direction inclined with respect to the front and back direction and intersected with the inside surface of the water supply portion 70 (as well as intersected with the outer peripheral surface of the bowl portion 8) as seen in plan view; and the water supply passage 91 is connected to a straight water supply tube 93 via a buffer chamber 92 which allows the flush water to temporarily stay.

In the example shown in FIG. 5, an entrance of the water supply passage 91 is located in the flow direction of the flush water from the straight water supply tube 93 into the buffer chamber 92.

The other structure of the third embodiment is substantially the same as the first embodiment explained with reference to FIGS. 1-3. In FIG. 5, the same portions as those of the first embodiment are shown by the same reference numerals, and detailed explanation thereof is omitted.

According to the above embodiment, since the flush water is allowed to temporarily stay in the buffer chamber 92, effects caused by a direction in which the flush water is supplied from the water supply tube 93 into the buffer chamber 92 can be reduced, so that the flush water can be more precisely supplied to the water supply section 70 along the direction of the water supply passage 91.

Herein, it is preferable to provide a wall that reduces the flow speed of the flush water at a position against a direction in which the flush water is supplied from the water supply tube 93 into the buffer chamber 92. Such an embodiment is shown in FIG. 6 as a fourth embodiment. FIG. 6 is a plan view showing a main toilet unit of a flush toilet according to a fourth embodiment of the present invention.

According to the fourth embodiment, since there is provided the wall 94 that reduces the flow speed of the flush water at a position against a direction in which the flush water is supplied from the water supply tube 93 into the buffer chamber 92, the effects caused by the direction in which the flush water is supplied from the water supply tube 93 into the buffer chamber 92 can be more reduced, so that the flush water can be much more precisely supplied to the water supply section 70 along the direction of the water supply passage 91. Herein, it is preferable that the inner wall surface of the wall 94 of the buffer chamber 92 is substantially perpendicular to the direction in which the flush water is supplied from the water supply tube 93 into the buffer chamber 92.

In addition, in a flush toilet according to the third embodiment or the fourth embodiment, it is preferable that the buffer chamber 92 has a bottom surface inclined downward toward the water supply portion 70. According to this feature, it can be inhibited that the flush water remains in the buffer chamber 92.

What is claimed is:

1. A flush toilet comprising:
a toilet main unit having a bowl portion,

a water conduit formed in the toilet main unit and configured to supply flush water into the bowl portion, wherein

the water conduit has: a first water-guiding portion extending from a water supply portion, where the flush water is supplied to the water conduit, to a first spout port located on one of right and left sides of the bowl portion; and a second water-guiding portion extending from the water supply portion to a second spout port located on the other of the right and left sides of the bowl portion, 10

the water supply portion is located at a right-sided or left-sided position in a right and left direction with respect to the bowl portion,

the flush water is supplied to the water supply portion in a direction toward an opposite side with respect to the right-sided or left-sided position of the water supply portion inclined with respect to a front and back direction and intersected with an inside surface of the water supply portion, as seen in plan view. 15

2. A flush toilet comprising:

a toilet main unit having a bowl portion,

a water conduit formed in the toilet main unit and configured to supply flush water into the bowl portion, wherein

the water conduit has: a first water-guiding portion extending from a water supply portion, where the flush water is supplied to the water conduit, to a first spout port located on one of right and left sides of the bowl portion; and a second water-guiding portion extending from the water supply portion to a second spout port located on the other of the right and left sides of the bowl portion, 25

the water supply portion is located at a right-sided or left-sided position in a right and left direction with respect to the bowl portion,

the flush water is supplied to the water supply portion in a direction inclined with respect to a front and back direction and intersected with an inside surface of the water supply portion, as seen in plan view, and the flush water is supplied to the water supply portion in a direction substantially perpendicular to a tangential direction of the inside surface of the water supply portion, 30

3. A flush toilet comprising:

a toilet main unit having a bowl portion,

a water conduit formed in the toilet main unit and configured to supply flush water into the bowl portion, wherein

the water conduit has: a first water-guiding portion extending from a water supply portion, where the flush water is supplied to the water conduit, to a first spout port located on one of right and left sides of the bowl portion; and a second water-guiding portion extending from the water supply portion to a second spout port located on the other of the right and left sides of the bowl portion, 40

the water supply portion is located at a right-sided or left-sided position in a right and left direction with respect to the bowl portion,

the flush water is supplied to the water supply portion in a direction inclined with respect to a front and back direction, 45

direction and intersected with an inside surface of the water supply portion, as seen in plan view, the flush water is supplied to the water supply portion by a straight nozzle extending in a direction inclined with respect to the front and back direction and intersected with the inside surface of the water supply portion, as seen in plan view,

the straight nozzle is connected to a water supply tube, and

the water supply tube has a proximal portion extending in the front and back direction, a distal portion connected to the straight nozzle and extending in the same direction as the straight nozzle, and a bend portion bending from the proximal portion to the distal portion.

4. A flush toilet comprising:

a toilet main unit having a bowl portion,

a water conduit formed in the toilet main unit and configured to supply flush water into the bowl portion, wherein

the water conduit has: a first water-guiding portion extending from a water supply portion, where the flush water is supplied to the water conduit, to a first spout port located on one of right and left sides of the bowl portion; and a second water-guiding portion extending from the water supply portion to a second spout port located on the other of the right and left sides of the bowl portion, 20

the water supply portion is located at a right-sided or left-sided position in a right and left direction with respect to the bowl portion,

the flush water is supplied to the water supply portion in a direction inclined with respect to a front and back direction and intersected with an inside surface of the water supply portion, as seen in plan view,

the flush water is supplied to the water supply portion by a bend nozzle,

the bend nozzle has a proximal portion extending in the front and back direction, a distal portion extending in a direction inclined with respect to the front and back direction and intersected with the inside surface of the water supply portion as seen in plan view, and a bend portion bending from the proximal portion to the distal portion, and

the bend nozzle is connected to a water supply tube extending in the front and back direction.

5. The flush toilet according to claim 1, wherein

the flush water is supplied to the water supply portion by a water supply passage extending in a direction inclined with respect to the front and back direction and intersected with the inside surface of the water supply portion, as seen in plan view, and

the water supply passage is connected to a water supply tube via a buffer chamber which allows the flush water to temporarily stay.

6. The flush toilet according to claim 5, wherein the buffer chamber has a wall formed at a position against a direction in which the flush water is supplied from the water supply tube into the buffer chamber.

7. The flush toilet according to claim 5, wherein the buffer chamber has a bottom surface inclined downward toward the water supply portion.
